No. 826,797.

PATENTED JULY 24, 1906.

E. NIEDERAUER.
UNION UNDERGARMENT.
APPLICATION FILED JUNE 5, 1905.

UNITED STATES PATENT OFFICE.

EDWARD NIEDERAUER, OF HAMILTON, OHIO.

UNION UNDERGARMENT.

No. 826,797.

Specification of Letters Patent.

Patented July 24, 1906.

Application filed June 5, 1905. Serial No. 263,697.

To all whom it may concern:

Be it known that I, EDWARD NIEDERAUER, a citizen of the United States, residing in Hamilton, Butler county, Ohio, (whose post office address is Hamilton, Ohio,) have invented certain new and useful Improvements in Union Undergarments, of which the following is a specification.

This invention, pertaining to improvements in union undergarments, will be readily understood from the following description, taken in connection with the accompanying drawings, in which—

Figure 1 is a rear view of a garment exemplifying my invention; Fig. 2, a front view of the same; Fig. 3, a view similar to Fig. 2, but illustrating a modification; Fig. 4, a rear view of the main portion of the unfinished garment, which I will herein term the "main garment;" Fig. 5, a plan of the outer flap-piece, and Fig. 6 a plan illustrating the manner of cutting the flap-pieces from the goods.

Attention is called to my Patent No. 700,801, granted May 27, 1902, and particularly to the construction of the rear placket therein, whereby a highly satisfactory degree of overlapping, fullness, and elasticity was secured. In that construction the rear placket flaps were flap-pieces attached to the main garment and having no other office than to furnish overlapping flaps for the rear placket and secure especial fullness at the seat. In the undergarment of that patent full-length legs were provided, and the main garment, quite independent of the rear flap-pieces, furnished the complete legs and the front placket. In thus considering my earlier patent I am referring only to the portion below the waist.

My present invention improves the garment whether with long or with short legs. I secure all of the peculiar merits of the rear placket of my earlier patent, but in addition cause the rear-placket pieces to join the main garment in forming the legs and also to themselves form the front placket, which front placket as thus formed may terminate at a point below the waist, or, if desired, it may join a breast-placket extended down to it, so as to form a complete placket extending continuously from the neck-front down and under the crotch and up the back to the waist, all the lower portions of this placket forming perfect overlaps and the construction being such as to secure a highly-satisfactory degree of economy in material and in seaming.

My improved union garment is made by first forming an incomplete main portion, which I will term the "main garment," and then adding to it two flap-pieces, which complete the main garment and form the continuous lower placket front and rear.

In the drawings, 1 indicates that incomplete main portion which I will term the "main garment," this main garment being 65 either knit or seamed or otherwise formed to shape as desired and its upper or breast and neck portion having any usual or desired character; 2, the legs of the main garment, which are shown of knee length, the form being such as to give to the outside lines of the legs that liberal flare so much desired in garments of this class; 3, an opening formed in the rear of the main garment and extending from about the waist-line to the base of the 75 legs; 4, the side edges of this opening, their upper portions preferably being characterized by strong inward convexities, in which respect the present construction is much similar to the garment set forth in my earlier 80 patent; 5, the top edge of this rear opening; 6, an opening in the front of the main garment, the same extending from the base of the legs up to a point some distance below the waist-line in front; 7, the side edges of 85 this front opening, the lines thereof being preferably concave, and 8 the apex of this opening, where the side edges meet. It is to be observed that this main garment has its legs incomplete and that the tops of the front 90 and rear openings are both far above the ultimate crotch of the garment, so that the garment is thus far incomplete not only as to the legs, but as to the front and rear.

Proceeding with the drawings, 9 indicates 95 an outer flap-piece; 10, its seaming edge in the form, preferably, of a reverse curve with its upper portion convex, this edge to be seamed to the left-hand edge 4 of the main garment; 11, the top edge of this outer flap-piece, the same to be seamed to the upper edge 5 of the rear opening of the main garment; 11^a, an upward cut in this outer flap-piece near the edge opposite the edge 10, this cut extending from the base of the flap-piece 100 upward to the height of the intended crotch of the garment, the line of this cut being a curve presenting its convexity toward the edge 10, a somewhat narrow tongue being thus left upon the edge of the piece opposite 105 the edge 10; 12, the concave edge of this flap-piece resulting from the cut 11^a, this edge 12

to be seamed to the edge 7 of the left-hand leg of the main garment from the base of the leg up to the extremity of the cut 11^a; 13, the tongue before referred to as resulting from 5 the cut 11^a; 14, the inner convex edge of this tongue, this edge to be seamed to the upper portion of the edge 7 of the left-hand leg of the main garment, that edge 7 thus having flap material seamed to it throughout its 10 length, the concave edge 12 of the flap-piece extending part way up the edge 7, while the convex edge of the tongue extends the balance of the way up the seam 7 to the apex 8; 15, the bending-point of the tongue 13 where the tongue is to bend forward and upward; 16, the point of the tongue; 17, the edge of the flap-piece 9 opposite the seamed edge 10, this edge 17 being a free or unseamed edge and when the flap-piece is seamed to the 20 main garment extending from the top 5 of the rear opening downward and then under the crotch and then forward and then up to the apex 8 in the front of the main garment; 18, the rear seam at the juncture of edge 10 25 of the outer flap-piece with the left edge 4 of the main garment; 19, the seam at the juncture of the top edge 11 of the outer flap-piece with the top edge 5 of the rear opening in the main garment; 20, the seam at the juncture 30 of edges 12 and 14 of the outer flap-piece with the left edge 7 of the main garment; 21, a tacking of the point of the tongue at the apex 8 of the main garment, this tacking extending down, say, two inches from the apex on 35 the right leg of the main garment; 22, a similar tacking of the point of the tongue to the left leg of the main garment, the free edge of the tongue thus terminating at a point somewhat below the apex of the front opening of 40 the main garment; 23, the outer rear flap of the placket as thus formed by the seaming to place of flap-piece 9; 24, the outer front flap of the placket as thus formed by the seaming to place of flap-piece 9, this combined front 45 and rear outer flap being continuous under the crotch, the free edge of the flap-piece extending from the level of seam 19 at the rear to the base of tacking 21 at the front; 25, a second flap-piece in all respects similar to 50 the flap-piece 9, except that it is right instead of left, this second flap-piece being similarly seamed to place in the main garment, but with reference to the right leg instead of the left one, this second flap-piece, however, underlying the first flap-piece, and thereby constituting the inner flap-piece of the placket; 55 26, the inner rear flap of the placket as thus underlying the outer rear flap-piece 23, and 27 the inner front flap thus underlying the 60 outer front flap 24. It is thus seen that the seaming into place of the two flap-pieces completes the legs and furnishes very liberal flaps for a placket extending downward at the rear and under the crotch and up the front. The placket is of such character that

it is thoroughly reliable at all of its portions, the construction being such that ample fullness is provided, together with a highly-desirable flare for the legs, and, as will be later explained, this is done practically without waste of material in forming the flap-piece.

As thus far described and as shown in Fig. 2 the front placket extends down only from a point some distance below the waist, both edges of the points of the tongue being tacked 75 to the front opening of the main garment. Such construction is consistent with a garment having either no breast-opening or having a comparatively short breast-placket, as at 28 in Fig. 2; but, if desired, the breast- 80 placket 28 may extend down to the apex of the front opening in the main garment, the inner flap of this long placket having its base joined to the upper extremity of the inner tongue, while the outer flap of this long front 85 placket may be seamed to the outer tongue, all as illustrated in Fig. 3, under which conditions there is formed a continuous placket extending from the neck down to and under the crotch and up the rear to near the waist-line. 90

By a peculiar manner of cutting the flap-pieces to be inserted in the main garment it can be done practically without waste, not, however, in the production of a single garment, but as a manufacturing operation 95 where garments are to be made in lots. This matter is illustrated in Fig. 6. Two layers of the fabric are taken and cut through, as indicated in Fig. 6. The piece 9 at the right forms the flap-piece for the left leg of the garment, being the piece illustrated in Fig. 5; but the piece at the left in Fig. 6 is not the flap-piece for the other leg of this garment, being, as will be observed, a duplicate of the piece at the right. In other words the piece 100 at the left is for the left leg of another garment; but the underlying piece of fabric produces also two of the pieces, and a given top piece, in connection with its underlying fellow piece, forms a right and left pair. One 105 cutting of the double thickness therefore produces two pairs of rights and lefts. If it should happen that the fabric is precisely the same on both faces, then, of course, a cutting such as is illustrated in Fig. 6 could produce 110 a right and left part from a single thickness of fabric.

Explanation has been given of the method of cutting the flap-pieces whereby a maximum of economy in material is secured. Attention will now be given to the main garment as illustrated in Fig. 4. The upper portion of this main garment will be shaped either by seaming or knitting; but the lower portion is given its shape by simple method 115 and without waste or seaming. Assume that we have in hand a piece of tubular webbing the total length of the garment, its upper portion having been seamed or knit to the body shape, its lower portion still re- 120

maining in the flat tube form. A single vertical cut is now made through both plies of this tube, this cut extending from the apex 8 to the base of the garment. A horizontal 5 cut (represented by the line 5) is then made in the upper ply only. A somewhat-triangular-shaped piece is then cut from the upper ply, the top line of the triangle being represented by the line 5, while its side lines will extend 10 from the ends of the line 5 down to the vertical cut first made. The two side portions of the under ply are then separated, thus forming the opening 6, and the side portions of the upper ply are still further separated, thus 15 forming the wider rear opening 3. In thus accomplishing the formation of the lower portion of the main garment it is to be observed that the triangular piece referred to represents the entire waste material. From 20 this description, which is demonstrative only, the manner of producing the lower portion of the main garment without material waste will be readily understood. In practical operations precisely the same result may 25 be advantageously arrived at by flattening

the tube in a direction extending from front to rear instead of from side to side of the garment, a single vertical slit at one folded edge forming when opened out the front opening 6, while a single vertical slit at the other folded edge of the tube, terminating above in an inward angular cut extended then outwardly, producing when opened out the wider rear opening of the main garment. 30

I claim as my invention—

As a new article of manufacture, a union bifurcated garment comprising a tubular fabric body portion and a leg portion, the leg portion being slit through both plies of the tube to form right and left leg portions, combined with right and left flap-pieces of approximately rectangular shape extending to the bottom of the leg portions and having relatively wide tops and bases, the flap-pieces having narrow side tongues cut thereon 45 adapted to form the front flaps of the placket. 40

EDWARD NIEDERAUER.
